G. EYLES.
SPIRIT LAMP.

Patented May 22, 1835.

May 22 1835 8840X⁵³

George Cyles of Boston State of Massachusetts

Letters Patent.

The Schedule referred to in these Letters Patent are making part of the same containing a description in the words of the said George Cyles himself of his Improvement in the lamp, for burning Volatile Materials.

To all whom it may concern.

Be it known that I George Cyles of the City of Boston in the State of Massachussetts, have invented an improvement in the lamp for burning Volatile materials, in the manner of what is sometimes called the spirit-gasp lamp. And that the following is a full and exact description thereof.

This lamp may be variously modified according to the purpose to which it is to be applied, or the taste of the manufacturer and in the drawings deposited in the Patent office. I have exhibited various modifications thereof, which it is not necessary here to describe, as the principle will be perfectly well understood by a specification of one of them. The body of the lamp, which is to contain the combustible ingredient may be of a globular form, and either suspended or placed upon a stand, and it may have any desired number of jets or burners. The flame is to issue from the lower part of the lamp, in order that it may communicate sufficient heat thence to vaporize the fluid and keep up the combustion. The tube is jet through which it issues has an open end within the lamp, above the fluid to allow the vapour to enter it, and it may descend either within, or on the outside of the body of the lamp, to its point of escape.

To fill the lamp. I insert a supply tube at, or near the upper part thereof which descends nearly to the bottom, thus allowing the fluid to be poured in, without danger of the escape of the vapour. Where a single jet only is used, it is of importance to be able to regulate the position of the tube, or of the lamp, as by this means the intensity of the combustion may be exactly governed; the size of the jet also must be such as is adapted to the flame required. In order to light the lamp in the first instance it must be warmed sufficiently to convert a portion of the fluid into vapour upon which it will keep up its own supply.

What I claim as my invention is the construction of a lamp for burning

volatile ingredients substantially upon the principle or in the manner herein disclosed, with all the variations of which the name is susceptible whilst a similar result is obtained by analogous means.
